UNITED STATES PATENT OFFICE.

STEPHEN COYNE, OF NEW YORK, N. Y.

IGNITION SYSTEM.

Application filed September 17, 1925. Serial No. 56,983.

This invention relates to improvements in ignition systems and more particularly to an automatic timer for advancing and retarding the spark in accordance with the speed of 5 the engine, to cause the engine to operate at its maximum efficiency.

An object of the invention is to provide an automatic timer in which the brush of the distributor and the breaker device of the 10 make and break mechanism are movable simultaneously to vary the horizontal planes with respect to the distributor contacts and the make and break contacts respectively, whereby to change the sparking impulses in 15 the ignition system in accord with the speed of the engine.

Another object resides in the provision of a timer in which the side edges of the distributor contacts are arranged at an angle 20 with respect to the axis of the rotation of the distributor brush, so that by changing the horizontal plane of said brush, will cause a variance in the time of the co-action of said brush and contacts during the rotation of the 25 brush.

A further object of the invention is to provide a means for adjusting the tension on the distributor brush and breaker device, against the lifting action produced by a governor 30 control mechanism, during the operation of the timer, so that the same may be accurately adjusted to a particular engine.

With these and other objects in view, the invention resides in certain novel construction and combination and arrangement of parts, the essential features of which are hereinafter fully described, are particularly pointed out in the appended claim, and are illustrated in the accompanying drawing, in 40 which:—

Figure 1 is a vertical sectional view through my improved automatic timer.

Figure 2 is a horizontal sectional view on the line 2—2 of Figure 1.

Figure 3 is an enlarged vertical sectional view through one of the distributor contacts.

Figure 4 is a detail perspective view of the breaker device.

Figure 5 is a diagrammatic view of an ignition circuit with my invention embodied therein.

Referring more particularly to the drawings, the reference numeral 10 illustrates my invention in its entirety which includes a distributor mechanism 11, a make and break

mechanism 12 and a governor control means 13, all of which are housed within a casing 14 of insulating material, having a removable cover or cap 15 held upon the casing by 60 clips 16 swingingly mounted upon the casing and co-acting with shoulders 17 on the cap.

The device 10 is supported upon the crank case 18 of an engine, by bolting the casing 14 thereto as at 19. A shaft 20 extends 65 within the crank case and has keyed thereto a gear 21 for constant meshing engagement with a gear 22 of the same diameter as the gear 21, which gear 22 is fixed to the cam shaft 23 journaled for rotation within the 70 crank casing 18.

From the foregoing description, it will be seen that shaft 20 will rotate at the same rate of speed as the shaft 23. The shaft 20 is journaled within the lower end of the 75 casing upon anti-friction bearings 24, to cause the same to freely rotate therein. The outer end of the shaft 20 is square in cross section as at 25, and fits within a correspondingly shaped bore 26 in the lower end of a 80 sleeve 27, which constitutes part of the governor control means 13.

The means 13 further includes a pair of opposed brackets 28 which extend outwardly and upwardly from the shaft 20 at the lower 85 end of the square portion 25. Brackets 28 pivotally support L-shaped arms 29, one leg of each of which carries a weight 30 while the other leg is formed with an inclined face 31 for co-action with the respective rollers 90 32 mounted upon the underside of a flange 33 provided on the sleeve 27. Springs 34 tend to normally hold the weighted end, of the arms 29 inwardly toward the shaft 20 as one end of each spring is attached to a collar 35 loosely mounted upon the sleeve 27, while the opposite end is connected to an adjustable member 36 carried by the upper leg of the respective arms 29. The member 36 on each arm is held in adjusted position 100 by a set screw 37, threadedly mounted within the arm 29.

The top end of the sleeve 27 is formed with teeth 38 for co-action with the toothed face 39 formed on the underside of the breaker 105 40 of the make and break mechanism 12. The member 40 is provided on its periphery with spaced angularly disposed ribs 41, there being six of such ribs shown in the drawings for actuating the pivoted contact member 42 of the make and break device. The member 42 is normally held in engagement with the 110

stationary contact 43 by means of a spring 44, but as the breaker rotates the ribs 41 will move the member out of engagement of the stationary contact 43 six times on each revolution of the breaker. The make and break device is arranged within the primary circuit at 45 of the ignition system and includes a switch 46 and a source of energy in the nature of a battery 47.

10 The breaker member 40 is formed with a reduced shank 48, and passing through the member and threaded into the sleeve 27, is a bolt 49 which serves to hold the teeth 38 and 39 in co-acting engagement. By loosening the bolt 49, the breaker member 40 may be adjusted to dispose the ribs 41 at different radial positions. It will, of course, be understood that the teeth 38 and 39 prevents slipping between the breaker member and the

20 sleeve during the rotation of the shaft 20.

Keyed to the shaft 48 is a distributor brush arm 50 which forms part of the distributor mechanism 11. The arm 50 is constructed of insulating material and carries

25 a metallic seat 51 disposed in alignment with the axis of the shaft 20. A metal strip 52 electrically connects the seat 51 with a metallic cylinder 53 mounted within the arm and in which cylinder is arranged a spring

30 pressed brush 54 for wiping engagement with the inner side walls of the cap 15. Held upon the seat 51 is a conductor member 55 slidably mounted within a metallic sleeve 56, which is provided at its top end

35 with a wire connector 57 which extends above a manipulating head 58 also constructed of insulating material. A spring 59 is interposed between the closed end of the sleeve and the conductor member 55 to

40 keep the member upon the seat 51. Tension of the spring may be adjusted by turning the head 58 to rotate the sleeve 56 with respect to the cap, and when adjusted a lock nut 60 threaded to the sleeve is moved down

45 against the cap. The distributor mechanism 11 is arranged within the secondary circuit 61 in which the wire leading to the secondary winding of a coil 62 is connected with a connector 57, from where the current

50 passes to the distributor brush 54 through the sleeve 56, member 55, seat 51, strip 52 and cylinder 53.

Countersunk within the inner walls of the cap 15 in the path of movement of the brush

55 54 are spaced contact plates 63, the side edges of which are disposed at an angle with respect to the axis of rotation of the brush arm so that by changing the horizontal plane of the brush arm, the brush will engage the

60 contacts at various intervals during the rotation of the arm.

When the brush rotates at a relatively low rate of speed, the arm is disposed to engage the lower ends of the plates, at which time the sparking action

65 is retarded, while gradual lifting of the arm

will cause the brush to engage the contact plates at an earlier time, thus advancing the sparking action. The plates 63 are arranged within the secondary circuit 61 and are connected by wires 64 which lead to the respective spark plugs 65. Six contact plates have been shown to correspond with the six ribs on the contact breaker, which is necessary when the device is intended for use in connection with a six cylinder engine. Of course, the number of contacts may vary according to the nature of the engine on which the device is adapted for use.

In operation, the shaft 20 is rotated when the engine is in operation, by the meshing gears 21 and 22, and the centrifugal force of the shaft tends to throw the weighted arms 29 outward against the tension of the springs 34.

As the arms move outward, the lower legs of the arms move upward which lifts the sleeve 27 by reason of the rollers 32 passing over the inclined faces 31. Vertical movement of the sleeve 27 changes the relative horizontal position of the ribs 41 on

the breaker mechanism with respect to the contact member 42, thus actuating the same at a different interval during the rotation of the breaker mechanism, thereby changing the time of the impulses sent through the primary circuit.

The distributor brush being fixedly connected to the member 40 also rises, thus changing its horizontal plane with respect to the side edges of the contact plates 63 which likewise changes the timing of the impulses sent through the secondary circuit.

The impulses are changed in timed accord so that the engine may operate at its maximum efficiency at all times during the retarding and advancing of the spark.

As the speed of the engine increases, the spark will be correspondingly increased by reason of the centrifugal action set up by the governor control means 13. As the speed of the engine decreases, the sleeve will gradually drop by reason of the action of the spring 59, at which time the weights 30

will move nearer the axis of the sleeve.

From the foregoing description, it will be seen that after the parts have been once adjusted to the conditions of an engine, the

same will operate in a manner to assure maximum efficiency, as the sparking is automatically controlled by the speed of the engine.

The cap 15 is provided with a window 66 to allow inspection of the distributor mechanism without removing the cap 15. Also, the casing 14 may have a door 67 therein for permitting access to the governor control mechanism.

While I have described what I deem to be the most desirable embodiment of my invention, it is obvious that many of the details may be varied without in any way departing from the spirit of my invention, and I

therefore do not limit myself to the exact details of construction herein set forth nor to anything less than the whole of my invention.

5 What is claimed as new is:—

A timing device including a rotatable shaft having a squared extension, a second shaft having a square socket for sliding movement over said squared extension and 10 having a brush arm on the top thereof adapted to successively engage a plurality of contacts, brackets extending from said mentioned shaft, L-shaped arms pivotally mounted in said brackets, one end of said arms

engaging rollers carried by flanges provided 15 on said second shaft, weights mounted on the free ends of said L-shaped arms, and contractile springs connecting said arms with said second shaft, whereby centrifugal force due to the rotation of said first shaft 20 will cause the weighted arms to lift said second shaft vertically to dispose said brush arm at varied horizontal positions with respect to the contacts with which it engages during rotation thereof.

25 In testimony whereof I have affixed my signature.

STEPHEN COYNE.
